UNITED STATES PATENT OFFICE

ERNEST L. PERSONS, OF NORTH ATTLEBORO, MASSACHUSETTS, ASSIGNEE TO MASON
BOX COMPANY, OF ATTLEBORO, MASSACHUSETTS, A CORPORATION OF MASSACHU-SETTS

DESIGN FOR A BOX TOP OR SIMILAR ARTICLE

Application filed November 19, 1931. Serial No. 41,785. Term of patent 3½ years.

To all whom it may concern:

Be it known that I, ERNEST L. PERSONS, a citizen of the United States of America, residing at 118 Division Street, in the city of North Attleboro, in the county of Bristol and Commonwealth of Massachusetts, have invented a new, original, and ornamental Design for Box Tops or Similar Articles, of which the following is a specification, reference being had to the accompanying drawing, forming a part thereof.

The figure is a perspective view of a box top showing my new design.

I claim:

The ornamental design for a box top or similar article as shown.

Signed by me at North Attleboro, in the county of Bristol, and Commonwealth of Massachusetts, this 30th day of October, 1931.

ERNEST L. PERSONS.
